UNITED STATES PATENT OFFICE.

JOHN DESMOND, OF WILMETTE, ILLINOIS.

DESIGN FOR A PUMP-CASING.

43,271.

Specification for Design.

Patented Nov. 26, 1912.

Application filed May 9, 1912. Serial No. 696,240. Term of patent 14 years.

To all whom it may concern:

Be it known that I, JOHN DESMOND, a citizen of the United States, residing at Wilmette, in the county of Cook and State of Illinois, have invented a new, original, and ornamental Design for a Pump-Casing, of which the following is a specification, reference being had to the accompanying drawing, wherein I have shown my new design.

Figure 1 shows an end elevation of my pump casing; and Fig. 2 a side elevation thereof.

The design shows in Fig. 1 a gradually tapering throat from the largest diameter of the crank case to the socket in which the cylinder is secured and an end disk having an annular rib around a central boss constit-

tuting an imperforate bearing support. Fig. 2 shows the throat uniformly narrower than the crank case and the socket, while at the other end of the cylinder the cylinder-receiving socket carries the intake and discharge valves and is approximately the same in diameter as the lower socket but is somewhat shorter. The base foot is extended laterally in Fig. 1 and is narrower than the crank case in the transverse view.

I claim:

The ornamental design of a pump casing as shown, and described.

JOHN DESMOND.
